ARTHUR ROTTER AND DAGOBERT DAVID, OF FRANKFORT-ON-THE-MAIN, GERMANY.

TYPE-INKING MECHANISM.

Application filed February 16, 1925, Serial No. 9,651, and in Germany April 16, 1924.

This invention relates to an inking device for the types of typewriting and similar machines with a reservoir for the ink adapted to oscillate against the action of a spring to get in the path of the type.

According to the invention the ink reservoir is tapered towards the point at which the type strikes, openings for the outflow of ink being arranged in this tapered part, said openings being covered with ink-absorbing material. The tapering shape of the reservoir forces the ink towards the outflow openings, the flow of ink being further assisted by the action of the centrifugal force occurring at the oscillation of the reservoir. In this manner a sufficient amount of ink is always supplied to the types.

Two embodiments of the invention are shown, by way of example, on the accompanying drawing, in which—

Figs. 1 and 2 show respectively in elevation and plan view the improved inking device and the corresponding parts of a type writing machine.

Fig. 3 is a cross section through the ink reservoir.

Figs. 4 and 5 show respectively in front elevation and plan view a second form of construction of the device.

On the one side face of a T-shaped flat iron *f* fixed on the type bar segment of a typewriting machine and carrying the head *g* for guiding the type an arm *b* is fixed which is approximately S-shaped and has an arm *b*¹ of circular cross section which serves as pivot axle for the ink reservoir *a*. This arm *b*¹ is parallel to the typing plane. The reservoir *a* is tapered at the end where the type strikes so that it has approximately triangular shape similar to a soldering copper, the small edge being rounded. A sleeve *j* which traverses the reservoir *a* is mounted on the arm *b*¹ so that the point of the reservoir projects in the path of the types *r*.

A spring *d*, the one end of which is fixed on arm *b* and the other end of which is inserted through an eye *e* projecting from the rear end of the reservoir *a*, serves to hold the reservoir normally in such position that it crosses the path of the types. In the top plate of the reservoir *a* an inlet opening closed by a screw with interposition of a packing is arranged, and outflow openings *i* (Fig. 3) for the ink are arranged in the

wall of the reservoir turned towards the types. These outflow holes *i* are covered by several layers *m* of silk.

The ink reservoir *a*¹ shown in Figs. 4 and 5 comprises a cylindrical part and a wedge shaped part forming a kind of snout. The holes *i* are arranged on the flat side of the snout, said snout being closed by a lid *k*¹. The holes *i* are covered by layers *m* of silk adapted to absorb the ink. The reservoir *a*¹ is mounted on the end *b*¹ of arm *b* said end of arm *b* serving as pivot pin. On the part of the end *b*¹ of pin *b* which projects over the reservoir a thin wire spring *d*¹ is wound, the one end of said wire spring is attached to the end *b*¹ of arm *b* and the other end to a pin *h* on the lid of the reservoir. On the bottom plate of the reservoir two pins *o*, *o*¹ are fixed at a certain distance apart the one opposite the other, and designed to limit the oscillating movements of the ink reservoir by bearing against the arm *b* and checking the action of the spring *d*¹.

When a type *r* is operated by the depression of a key, a push lever or oscillating lever or the like, it strikes against the end of the ink reservoir in which the silk covered outflow openings *i* are arranged, so that the face of the type is inked and the reservoir oscillates around its pivot axle *b*¹ against the action of the spring (position shown in Fig. 2 in dash lines). When the type moves back the ink reservoir is returned to its position of rest by the action of the spring *d* or *d*¹.

Owing to the tapered shape of the ink reservoir *a* the ink flows towards the point or outlet openings *i*, and by the oscillating movement of the reservoir a centrifugal force is produced which forces the ink towards the silk cover *m* so that this cover is always soaked with ink and a thorough inking of the types is ensured.

We claim:—

1. An inking device for the types of typewriting and similar machines comprising in combination an ink reservoir having a tapered front end, means to position its front end in the path of any type key upon depression of such type key, the tapered front end of the ink reservoir having outflow openings, and an ink pad over the outflow openings.

2. An inking device for the types of type-

writing and similar machines comprising in combination an ink reservoir having a tapered front end, means to position its front end in the path of any type key upon depression of such type key, the tapered front end of the ink reservoir having outflow openings, and an ink pad over the outflow openings,

elastic means to bias the reservoir to position the front end in the type key's path. In testimony whereof we affix our signatures.

ARTHUR ROTTER.
DAGOBERT DAVID.
